US0D1082663S

(12) **United States Design Patent** (10) Patent No.: **US D1,082,663 S**
(45) Date of Patent: ** Jul. 8, 2025

(54) **BATTERY CHARGER HOUSING**

(71) Applicant: **Suzhou Yihang Electronic Science and Technology Co., Ltd.**, Jiangsu (CN)

(72) Inventors: **Wei Yang**, Jiangsu (CN); **Tao Yang**, Jiangsu (CN); **Ning Ye**, Jiangsu (CN)

(**) Term: **15 Years**

(21) Appl. No.: **29/878,078**

(22) Filed: **Jun. 15, 2023**

(30) **Foreign Application Priority Data**

May 10, 2023 (CN) 202330270759.1

(51) **LOC (15) Cl.** **13-02**

CLAIM

The ornamental design for a battery charger housing, as shown and described.

DESCRIPTION

FIG. 1 is a front perspective view of a battery charger housing showing our new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear perspective view thereof; and,

FIG. 9 is an enlarged view of the battery charger housing taken from the circle part in FIG. 1.

The broken lines in the drawings depict portions of the battery charger housing that form no part of the claimed design.

1 Claim, 9 Drawing Sheets
